UNITED STATES PATENT OFFICE

JAMES HENRY CARTNER BOYD, OF SLOUGH, ENGLAND.

SCISSORS, SHEARS, AND LIKE IMPLEMENT.

Application filed August 3, 1926, Serial No. 126,814, and in Great Britain May 20, 1926.

This invention relates to scissors, shears and like implements of the type comprising a pair of scissor-like elements or carriers on each of which is detachably mounted a thin flat blade or cutting element and has for its object to permit the ready attachment of the blades to the carriers without the necessity of using a screw driver or any special tool, so that blunt blades may be replaced with great facility.

The improved scissors comprise a pair of scissor-like elements or carriers, and thin blades or cutting elements detachably supported on said carriers, each carrier being formed (a) near the tip of the blade-carrying portion thereof with a longitudinally extending undercut recess adapted to receive a correspondingly offset longitudinally extending tongue on a blade, (b) near the butt end of said portion with a transversely extending undercut slot adapted to receive the butt end of a blade, and (c) with a longitudinally extending rib adapted to support the back edge of a blade, the carriers and the blades being apertured to give passage to the pivot pin of the implement, whereby the blades are secured in position on the carriers and the carriers are secured and pivoted to one another.

The invention is illustrated, by way of example, in the accompanying drawings wherein Figure 1 is a front elevation of a pair of scissors, Figure 2 is a partial side elevation, Figure 3 is a partial front elevation of a blade carrier, Figure 4 is a front elevation and Figure 5 a side elevation of a blade, Figures 6, 7 and 8 are cross-sections on the lines 6-6, 7-7 and 8-8 respectively, Figure 1 on an enlarged scale showing details.

As illustrated a pair of scissor-like elements or carriers *a b* are pivoted together by a pin *c* and each carries a thin blade or cutting element *d*. Each carrier *a b* is formed near its tip with a longitudinally extending undercut recess *e* adapted to receive a correspondingly off-set longitudinally extending tongue *f* on a blade *d*, (as shown especially in Figure 7), the free end of said tongue extending towards the butt end of the blade so that longitudinal movement of the blade towards the pivot pin *c* is necessary to effect engagement. At the butt end of its blade-carrying portion each

carrier *a b* is formed with a transversely extending undercut slot *g* adapted to receive the butt end of a blade *d* (see especially Figure 8), when moved longitudinally as aforesaid, the engagement of both ends of a blade with a carrier serving to hold the former in position during assembly and to some extent when assembled. The undercut groove *g* in the carrier *a* is formed beneath an arcuate boss *h* (see Figure 3) the surface of which is inclined to the general plane of said carrier as also is the opposing face of the carrier *b* so as to serve as cams for forcing together the cutting edges of the blades *d d* as is well known in scissors. Each carrier *a b* is formed also with a longitudinally extending rib *j* adapted to support the back edge of a blade *d* when in use said rib being of such size as to be flush with the surface of said blade *d*. The carriers *a b* and the blades *d d* are apertured as at *k* and *m* respectively (Figures 3 and 4) to give passage to the pivot pin *c* and the latter is formed at one end with a flat head *n* and near its other end with a peripheral groove *o* (see Figure 8). The carrier *a* has slidably mounted thereon a locking plate *p* slotted as at *q* to give passage to a headed securing rivet *r* and key-hole slotted as at *s* on the one hand to give passage to the pivot pin *c* and on the other hand to engage in the peripheral groove *o*, the plate *p* being bowed so as to present frictional resistance against longitudinal movement and furnish with an upstanding end *t* to enable it so to be moved for the purpose of locking or unlocking the parts.

The cams for the purpose of forcing together the cutting edges of the blades *d d* may be formed on the blades themselves (instead of on the carriers) by stamping out therefrom inclined arcuate ribs.

Inasmuch as a blade *d* can be placed in position by a mere longitudinal sliding movement it is unnecessary to ensure careful registry of several apertures and securing means such as screws or rivets as are sometimes employed with detachable blades, and this coupled with the similar longitudinal movement of the locking plate *p* enables the parts to be assembled or separated very readily without the use of a screw driver or any special tool or the necessity of undoing any thumb or other screws. In use the

blades *d* are held securely in position and their fastening means are relieved of all strain by the ribs *j*, *j*.

I claim:—

5. 1. A scissors comprising a pair of blade carrying elements, thin metal cutting blades adapted detachably to be supported on said elements, each of said blade carrying elements being provided with a longitudinally 10 extending under-cut recess near its tip end, a transversely extending under-cut slot near its butt end and a longitudinally extending rib for supporting the back edge of the blade, each of the respective blades being provided 15 with an off-set longitudinally extending tongue for cooperation with the under-cut recess of the corresponding blade carrying element, while the butt end of the blade is adapted to enter the corresponding transverse under-cut slot, said carrying elements and the blades being provided with coincident pivot 20 apertures, a pivot passing through said apertures and means for removably securing said pivot so that the blades may be changed when 25 desired.
2. A scissors comprising a pair of carrier members, each provided with a pivot aperture, adapting the carrier members to be pivoted together, and an under-cut recess near 30 the tip end thereof, the under-cut surface of which lies transversely of the carrier member and extends at an angle toward the pivot, a rib extending as a laterally projecting flange along the back edge of each carrier member, 35 said rib being of substantially the same thickness as and adapted for supporting the back edge of a detachable blade, a detachable thin metal scissors blade for each carrier member, each blade being provided with a pivot aperture adapted to register with the pivot aperture 40 of the corresponding carrier member and a punched-out tongue near the tip end of the blade, having its face lying transversely of and its free end extending at an angle to-

ward the pivot end of the blade and adapted 45 for cooperative engagement with the corresponding under-cut recess of the carrier member, said engagement being effected by a sliding movement of the blade longitudinally along the face of the carrier member in the 50 direction of the pivot, and a pivot pin passing through said pivot apertures for securing the carrier members together and for holding the respective blades in position, the arrangement and relative dimensions being 55 such that when pivoted together the tongues of the blades fit loosely in the respective under-cut recesses of the carrier members so as to take none of the cutting thrust, all of which is adapted to be taken by the ribs 60 of said carrier members.

3. The scissors as claimed in claim 2, wherein the tongues of the blades are adapted to fit in the under-cut recesses so loosely as to permit the backs of the blades to engage 65 said ribs so that the latter take the entire cutting thrust of the blades, and said ribs extend beyond the recesses in the carrier members so as to take the thrust of the blades beyond the tongues thereof. 70

4. A carrier member for detachable scissors blades, provided with a pivot aperture and an undercut recess, the latter being between the pivot aperture and the tip end of said member and having the under-cut surface thereof lying transversely of the member and extending at an angle toward the pivot aperture, and a rib comprising a flange projecting laterally of the face of the member, approximately the thickness of the blade to 75 be used, and extending along the back of said member for supporting the back of the detachable blade, said rib extending beyond said under-cut recess so as to provide a support for the end of the blade at and beyond 80 said recess. 85

JAMES HENRY CARTNER BOYD.
